ISOMERIZATION OF NORMAL BUTENE

Charles L. Thomas and Herman S. Bloch, Chicago, Ill., assignors to Universal Oil Products Company, Chicago, Ill., a corporation of Delaware

No Drawing. Application February 9, 1939,
Serial No. 255,480

8 Claims. (Cl. 260—683)

This invention relates particularly to the treatment of normal butenes to transform them into isobutene.

More specifically this invention comprises the novel process for accomplishing this particular isomerization reaction employing particular catalysts and conditions of operation. The butenes comprise the mono-olefins containing 4-carbon atoms per molecule. The names of these hydrocarbons, their structures, and boiling points are given in the following table for purposes of reference:

16	Name	Structure	Boiling point, °C.
17	1-butene.....	CH ₃ CH ₂ —CH=CH ₂	—5
20	2-butene, cis.....	$\begin{array}{c} \text{H} \text{C} \text{—} \text{CH}_2 \\ \parallel \\ \text{H} \text{C} \text{—} \text{CH}_2 \end{array}$	+1-1.5
24	2-butene, trans.....	$\begin{array}{c} \text{H} \text{—} \text{C} \text{—} \text{CH}_2 \\ \\ \text{CH}_3 \text{—} \text{C} \text{—} \text{H} \\ \\ \text{CH}_3 \end{array}$	+2.5
28	Iso-butene.....	$\begin{array}{c} \text{CH}_3 \\ \\ \text{C} \text{—} \text{CH}_2 \\ \\ \text{CH}_3 \end{array}$	—6

Recently the butenes have become of considerable importance to the petroleum industry as a result of the demand for high antiknock fuel suitable for use in high compression aviation engines. They occur as constituents of cracked gases formed in plants operating primarily to produce gasoline and can also be produced by the catalytic dehydrogenation of butanes which occur in large quantities in wet natural gases and in still and tank gases of petroleum refineries. The butenes and butanes are utilizable as such only in limited quantities on account of their relatively high vapor pressures and at the present time there is considerable over-production of them so that processes are being developed for their more efficient utilization.

The steps in preparing octanes for use as high antiknock saturated aviation motor fuel consists, at the present time, in first polymerizing butenes by either thermal or catalytic processes and then hydrogenating the resultant octene fractions. As a result of many investigations it has been determined that the octanes having the highest antiknock value are those which have the most compact molecules, or in other words the greatest branched-chain structures. Further, it has been shown that the dimers of isobutene, which correspond largely to 2,4,4-trimethyl-1-pentene

and 2,4,4-trimethyl-2-pentene on hydrogenation yield octane fractions of considerably greater antiknock value than do the dimers produced by the direct polymerization of the normal butenes, or by mixed polymerization of isobutene and normal butenes. In actual numerical values, using 2,2,4-trimethyl pentane as a standard of reference of 100 octane number, the hydrogenated dimers of isobutene have octane numbers of 97-100; those of normal butenes from 83 to 85, and 10 hydrogenated mixed dimers from 90 to 97. These data are only approximate as it has been found that the actual values vary with the conditions of polymerization. It is obvious from the foregoing that any increase in the relative percentages of isobutene in hydrocarbon gas mixtures is very desirable and it is the object of the present invention to provide a process for accomplishing this object.

In one specific embodiment the process of the present invention comprises subjecting gases containing normal butenes at elevated temperatures under atmospheric or relatively low superatmospheric pressure, to contact with catalytic materials comprising synthetically prepared calcined mixtures of the hydrogels of silica (SiO₂), alumina (Al₂O₃), and thoria (ThO₂) for the conversion of said normal butenes into isobutene.

In the following specification the term "Silica-alumina-thoria" masses is used in its broadest sense. Inasmuch as the chemical knowledge of the solid state is imperfectly developed, it is not possible to give the structure of all solid substances. All that can be said definitely concerning the "silica-alumina-thoria" masses is that they contain silica, alumina, and thoria in some combination or combinations. We have specifically described the catalytic masses used in the process of this invention and have arbitrarily referred to them as "silica-alumina-thoria" masses for lack of a more appropriate term.

According to the present invention, normal butenes contained in gas mixtures, such as are formed by dehydrogenation of butane, or as remain in butane-butene fractions after removal therefrom of isobutene by selective methods, such as polymerization in the presence of catalysts comprising solid phosphoric acid, sulfuric acid solutions and others, are isomerized to a substantial degree into isobutene by contact at elevated temperatures with silica-alumina-thoria catalysts.

The preferred isomerization catalysts may be prepared by a number of alternative methods which have certain necessary features in common

as will subsequently be described. Generally speaking, however, the catalysts may be considered to comprise an intimate molecular combination of silicon, aluminum, thorium, and oxygen, all of the components of which possess more or less low activity individually but display high activity in the aggregate. The activity is not an additive function, it being relatively constant for a wide range of proportions of the components 10 whether in molecular proportions or fractions of molecular proportions. No one component may be determined as the one component for which the remaining components may be considered as the promoters according to conventional terminology, nor can any component be determined as the support and the others as the catalyst proper.

According to one general method of preparation the preferred catalyst may be prepared by precipitating silica from a solution as a hydrogel 20 and subsequently admixing or depositing the hydrogels of alumina and thoria upon the hydrated silica. One of the more convenient methods of preparing the silica hydro-gel is to acidify an aqueous solution of sodium silicate by the addition of an acid, such as hydrochloric acid, for example. The excess acid and the concentration of the solution in which the precipitation is brought about determine in some measure the suitability 30 of the silica hydrogel for subsequent deposition of the hydro-gels of alumina and thoria. In general, suitable hydrated silica may be produced by the use of dilute solutions of sodium silicate and the addition of a moderate excess of acid whereby the desired active silica gel is obtained and conditions of filtering and washing are at an optimum.

After precipitating the silica hydrogel, it is treated and washed to substantially remove alkali metal ions. It is not known whether the alkali metal ions, such as sodium ions, are present in the primary gel in chemical combination, or in an adsorbed state but it has been determined definitely that their removal is necessary if catalysts are to be obtained suitable for prolonged use in accelerating hydrocarbon conversion reactions of the present character. It is possible that the presence of the alkali metal impurities causes a sintering or fluxing of the surfaces of the catalyst at elevated temperatures so that the porosity is much reduced with corresponding reduction in effective surface. Alkali metal ions may be removed by treating with solutions of acidic materials, ammonium salts, or salts of aluminum and thorium. When treating with acids, as for example with hydrochloric acid, the acid extracts the alkali metal impurities in the silica gel. The salts formed and acid are then substantially removed by water washing treatment. Where ammonium salts, or salts of aluminum and thorium are used, the ammonium or multivalent metals used apparently displace the alkali metal impurities present in the composite and the alkali metal salts formed, together with the major portion of the multivalent salts, are removed in the water 50 washing treatment. Some of the multivalent metals introduced into the silica hydrogel in the purifying treatment may become a permanent part of the composite, whereas in the treatment with ammonium salts small amounts of the ammonium salts remaining after the washing process will be driven off in subsequent treatment at elevated temperatures.

In one of the preferred methods of composing the hydrogel materials, the purified precipitated 75 hydrated silica gel may be suspended in a solu-

tion of thorium and aluminum salts in the desired proportion and thoria and alumina hydrogels deposited upon the suspended silica hydrogel by the addition of volatile basic precipitants, such as ammonium hydroxide, for example, or ammonium carbonate, ammonium hydrosulfide, ammonium sulfide, or other volatile basic precipitants, such as organic basis, may be employed. According to this method, the purified silica gel may be suspended in a solution of thorium nitrate 10 and aluminum chloride, for example, and the hydrated thoria and hydrated alumina precipitated by the addition of ammonium hydroxide. In this example, the alumina and thoria are co-precipitated.

Alternatively the purified hydrated silica gel may be mixed while in the wet condition with separately prepared hydrated alumina and hydrated thoria precipitated either separately or concurrently as for example, by the addition of 20 volatile basic precipitants to solutions of aluminum and thorium salts. The hydrated alumina and hydrated thoria thus prepared are substantially free from alkali metal ions and can be admixed with the purified silica gel. However, if 25 alkali metal ions are incorporated as when the hydrated alumina is prepared from sodium aluminate, for example, or if thorium tetrabehydroxide is precipitated by the interaction of thorium nitrate and sodium hydroxide, regulated purification treatment and water washing, by methods selected from those described in connection with the purification of the hydrated silica gel to remove alkali metal ions, will be required. Care should be observed in the selection and concentration of reagents used so as not to dissolve unduly large amounts of alumina or thoria. As further alternatives, the purified silica gel may be added to a solution of salts of aluminum and thorium and hydrated alumina and hydrated 30 thoria deposited by hydrolysis with or without the use of heat, or the purified silica gel may be mixed with suitable amounts of salts of aluminum and thorium as, for example, in forming a paste and heating whereby alumina and thoria are deposited upon the silica gel as a result of the decomposition of the aluminum and thorium salts. 35

In the methods above described, a silica hydrogel free from alkali metal ions was admixed or had deposited thereon relatively pure hydrated alumina and hydrated thoria prior to drying treatment. In methods described below, the hydrated silica, hydrated alumina and hydrated thoria are concurrently precipitated or admixed and treated to remove alkali metal ions from the composited material prior to drying treatment either in the presence of the original reactants or subsequent to water washing. Thus, solutions of silicon compounds, more usually alkali metal silicates and soluble aluminum and thorium salts, 40 may be mixed under regulated conditions of acidity or basicity to jointly precipitate hydrated silica, hydrated alumina, and hydrated thoria in varying proportions. For example, solutions of sodium silicate, aluminum chloride, and thorium nitrate may be mixed and alkaline or acid reagents added according to the proportions used so that a pH in the range of 3-10 is obtained. In cases where a sol is formed the precipitation may be brought about if the sol is acid by the addition 45 of a volatile base, as for example, ammonium hydroxide, and alkali metal salts removed by water washing, or the composite may be treated as indicated above in connection with the purification of the hydrated silica to remove alkali metal ions. 50

Various methods are possible for the preparation of the hydrated silica, hydrated alumina and hydrated thoria separately or in combination and the purifying treatment is necessary where alkali metal ions are present in substantial amounts.

The character and efficiency of the ultimately prepared silica-alumina-thoria catalyst will vary more or less with precipitation and/or mixing, purification treatment, ratio of components, calcining, etc., several specific examples being given below. The ratio of the components may be varied within wide limits, the limiting factor being more in evidence with respect to small proportions than with large proportions of the various components. In general, it appears that two or six mole per cent of alumina and thoria together with reference to silica may be considered an approximation of the minimum proportions. Because thorium is relatively expensive it is generally desirable to use a relatively low proportion in the order of less than one mole per cent of the total catalyst.

After the alumina and thoria have been mixed with or deposited upon the purified hydrated silica gel and water washed, if desired, as described for one general method of preparation, or after the hydrated silica, hydrated alumina, and hydrated thoria have been composited and treated to remove the alkali metal ions, as described for another general method of preparation, the catalytic materials may be recovered as a filter cake and dried at a temperature in the order of 240-300° F. more or less, after which it may be formed into particles of a suitable average definite size ranging from powder to various forms and sizes obtained by pressing and screening, or otherwise formed into desired shapes by compression or extrusion methods.

By calcining at temperatures of the order of approximately 850-1000° F., or higher, the maximum activity of the catalyst is obtained and a further dehydration occurs so that, for example, after a considerable period of heating at 900° F., the water content, as determined by analysis, is of the order of 2-3%.

Catalysts prepared by the various types of procedures outlined evidently possess large total contact surfaces corresponding to a desirable porosity, the pores of the catalyst particles being of such size and shape that they do not become clogged with carbonaceous deposits after a long period of service and are, therefore, not difficult to reactivate by oxidation. This structure is retained, also, after many alternate periods of use and reactivation as evidenced by the fact that the catalysts may be reactivated rapidly by passing air or other oxidizing gas over the used particles to burn off the deposits of carbonaceous material at temperatures above 800° F., temperatures as high as 1400-1600° F., having been reached without apparently affecting the catalytic activity.

In conducting the process for the isomerization of normal butenes the simplest mode of operation is to preheat the butenes, or gas mixtures containing them, to a temperature in the desired approximate range during passage through some type of effective tubular heater, and then introducing the preheated gas into a chamber containing a section, or a number of sections of the granular catalyst, in which the time of contact is so regulated that there is optimum production of isobutene. The catalysts filling such catalyst sections may have particle sizes within the approximate range of 1-14 mesh, which may apply either to pellets of uniform

size and of cylindrical shape, or to particles of irregular size and shape produced by the grinding, consolidating, and sizing of the partially dehydrated material. As will be shown in later examples, some polymerization is unavoidable and the next step in the process, after contacting with the catalyst, will be the separation of liquid polymers and the further segregation of the gaseous components so that the isobutene produced is available for selective polymerization under conditions most suitable for the formation of its dimers and the residual normal butenes may be recycled to further contact with the catalyst.

Since as a rule the normal butenes and isobutene in the resultant gas mixture will correspond to substantially a relatively constant proportion of these two components, a procedure is suggested which involves their mixed polymerization to form iso-octenes without attempting to separate the gaseous reaction products. This polymerization may be effected under revised conditions of operation using a suitable catalyst, such as solutions of sulfuric acid, metal phosphates as calcium and cadmium, the so-called "solid phosphoric acid" catalyst, or the types of synthetic silica-alumina-thoria catalysts mentioned above, which involves preferably the segregation of the butane-butene fraction from the light gases and any extremely heavy products and the subjection of the recovered intermediate butane-butene fractions to polymerization. Each polymerization catalyst, which may be used alternatively, will exert its own specific influence, will not be identical with that of other members of the class, and will require particular conditions for effecting optimum results.

Use of the "solid phosphoric acid" catalyst for such polymerization is preferably effected under what may be termed "critical" phase conditions; namely, pressures of approximately 500-700 pounds per square inch, temperatures of 225-325° F., and preferably a long time of contact in the order of 100-350 seconds. Under these conditions 4-carbon atom hydrocarbons may be considered to exist as extremely heavy vapors, and it has been found that mixed polymerization of isobutene and normal butene is favored so that properly proportioned mixtures are converted almost quantitatively into mixtures of iso-octenes, which are readily hydrogenatable, to a large extent, into 2,2,4-trimethylpentane, the standard of reference in antiknock test work.

The synthetic silica-alumina-thoria catalysts may be used at a relatively high temperature for long periods of time substantially without diminution in isomerizing activity. Such activity, which decreases probably because of carbon deposition, may be restored by heating the catalytic material in a current of air, or in large commercial installations in a flue gas mixture containing a controlled oxygen concentration; so as to burn off the carbonaceous deposit without overheating the catalyst. After such burning treatment, the catalyst is active and ready for use.

While the chemical reactions involved in the isomerization of normal butenes into isobutene are not understood clearly or completely, the following is suggested as a mechanism of the reactions involved:

In contact with synthetic silica-alumina-thoria catalysts the normal butenes may be considered to undergo polymerization reactions forming normally liquid products as octenes, together with trimers, tetramers, and higher polymers which later suffer so-called "Depoly-

merization" or catalytic splitting reactions producing isobutene, normal butenes, and liquid products of lower boiling points than the originally-formed polymers. In view of the complexity of such a combination of polymerization and splitting reactions, it is obvious that the above mechanistic concept may not express the exact course of the reactions involved; and, accordingly, the concept should not be misconstrued so as to limit the invention.

The following numerical data are introduced to indicate some of the results obtainable in isomerizing normal butenes by the present process, although it is not intended to limit the scope of the invention in strict accordance therewith:

An isomerization catalyst prepared according to the process of the present invention consisted of a mass corresponding approximately to 200 moles of silica (SiO_2), 10 moles of alumina (Al_2O_3) and 1 mole of thoria (ThO_2). The general procedure observed in preparing this catalyst was to precipitate silica gel, wash and treat to free it from alkali metal ions, suspend the purified precipitated silica in a solution of aluminum chloride and thorium nitrate, and precipitate hydrogels of alumina and thoria in the presence of the suspended silica hydrogel by the use of ammonium hydroxide.

1650 parts by weight of a commercial grade of sodium silicate (equivalent to 8 moles of SiO_2) was diluted with 7000 parts by weight of distilled water. A solution of hydrochloric acid (5 normal) was prepared by diluting 562 parts of concentrated (12 normal) hydrochloric acid with water to a total volume corresponding to 1350 parts. The dilute hydrochloric acid solution was added gradually to the diluted sodium silicate (stirred mechanically) which was then further diluted by the addition of 1000 parts of water. After the addition of the total quantity of the dilute acid solution, the precipitated silica hydrogel was collected on a filter, then slurried in 4000 parts of water and again filtered, this operation being repeated several times. Secondly, in order to remove the alkali metal ions still remaining as impurities in the washed silica gel by further treatment with dilute hydrochloric acid, the silica gel was slurried in 4000 parts of water containing 40 parts of the diluted (5 normal) hydrochloric acid, the treatment being repeated twice. The precipitate was then subsequently washed several times with water, with 4000 parts by volume of an aqueous solution containing 21 parts by weight of ammonium chloride and then several times with water.

1160 parts by weight corresponding to 2.8 molecular portions of the purified silica hydrogel was suspended in 3000 parts of an aqueous solution containing 67.6 parts by weight of aluminum chloride hexahydrate (0.28 molecular portions) and 7.72 parts by weight of thorium nitrate tetrahydrate (0.014 molecular portions). To this suspension approximately 75 parts by weight of concentrated ammonium hydroxide solution was added with stirring until the reaction mixture was basic to litmus, after which the precipitated silica-alumina-thoria mass was collected on a filter. The filter cake was dried by heating in air for approximately 16 hours at a temperature increasing gradually from 220° to 300° F. The dried powder was then pressed and broken up to obtain approximately 6-10 mesh sized particles which were calcined in a stream of dry air at

approximately 900° F. for 6 hours, during which time moisture and some ammonium chloride were expelled from the catalytic mass.

Isomerization runs were made on a dry so-called "de-isobutene" butane-butene fraction obtained as outlet gas from a polymerization process operating on a 4-carbon fraction of refinery gases to produce from isobutene and normal butenes a substantial yield of iso-octenes hydrogenatable to iso-octane fractions of high antiknock value. This charging stock, containing 1.6% isobutene, 19.4 normal butenes, 70.7% butane, 5% of propene and propane, and 3.3% pentanes and higher hydrocarbons, was passed downwardly through a heated tube containing 6-10 mesh particles of silica-alumina-thoria catalyst which had been activated by heating previously for 6 hours at 900° F. in a stream of air at atmospheric pressure. Before this activation treatment the particles or granules of the catalyst had been formed by pressing the powdered silica-alumina-thoria mixture into a hard cake by means of an hydraulic press, and then crushing this cake and screening the granules to the desired mesh size.

The results obtained in these laboratory scale runs showed that isomerization of normal butenes into isobutene increased with temperature rise. Also, it was found that considerable polymerization occurred at long times of contact, but was avoided to a substantial degree at shorter times of contact. Under the heading "polymerization and loss" of Table 1 are included the conversions of the normal butene content of gas mixtures into heavier and lighter products. Such formation of propene and lighter gases, at the expense of the butenes, occurred to a substantial degree in other runs when pure butenes were subjected to temperature in the order of 1100° F. using low space velocities (volumes of gas per hour per volume of catalyst) in the approximate range of 200-400.

TABLE I
Isomerization of normal butenes into isobutene in the presence of silica-alumina-thoria catalyst

Temp., ° F.	Contact time, seconds	Space velocity	Isomerization, percent	Polymerization and loss, percent
842	3.0	236	17.7	41.0
842	0.8	885	20.5	11.2
845	0.37	1885	18.0	9.5
843	0.23	2830	16.5	2.4
933	0.7	944	20.5	22.4
935	0.35	1888	17.0	13.9
938	0.23	2832	15.1	5.7
941	0.17	3820	13.9	0

After the runs at 842° F., which lasted approximately 2 hours, the catalyst was as hard as when charged, but black with a carbonaceous deposit on both the exterior and interior of the particles. It was then reactivated by heating in a stream of dry air for 6 hours at 900° F., and restored to its original white color and substantially unchanged isomerizing activity. Subsequent use of this reactivated catalyst at 930-940° F., gave the results shown in the above table.

In isomerization plants of commercial dimensions the relationship of isomerization to conditions of operation may not necessarily be the same as observed in small runs made in laboratory apparatus.

The silica-alumina-thoria catalyst retained its

isomerizing activity through a large number of alternate runs and reactivations. Such a used catalyst was reactivated anew and subjected to a life test at 842° F., using space velocities of approximately 210-240, which corresponded to contact times of approximately 3 seconds. As shown by the results in Table 2, the percentage isomerization started at 21.9% and continued at an average value of 19.8% during 114 hours, after which the catalyst was reactivated at 900° F., as above described.

TABLE 2
Butene isomerization life test in the presence of
a silica-alumina-thoria catalyst

	Time on test, hours	Isomerization, percent
20	1	21.9
	3-4	17.2
	16-17	19.6
	40-41	21.9
	68-69	21.7
	80-81	18.5
	93-94	16.5
	113-114	21.1
25	Average	19.8

The foregoing specification and limited numerical data will serve to indicate the character of the process of the present invention and the nature of the results to be expected in its practice, although neither section is introduced with the idea of unduly limiting the invention's generally broad scope.

We claim as our invention:

1. A process for converting normal butenes into isobutene which comprises contacting said normal butenes at a temperature in the approximate range of 700-1100° F. with catalytic material comprising essentially a synthetically prepared composite mass of silica, alumina, and thoria.
2. A process for converting normal butenes into isobutene which comprises contacting said normal butenes with catalytic material comprising essentially a synthetically prepared composite mass of silica, alumina, and thoria, at a temperature in the approximate range of 700-1100° F., under a pressure in the approximate order of 0.05-5.0 atmospheres.
3. A process of isomerizing into isobutene a substantial portion of the normal butene content of essentially 4-carbon atom hydrocarbon frac-

tions, substantially free from isobutene, which comprises contacting said hydrocarbon fractions with catalytic material comprising essentially a synthetically prepared composite mass of silica, alumina, and thoria at a temperature in the approximate range of 700-1100° F.

4. A process for isomerizing into isobutene a substantial portion of the normal butene content of essentially 4-carbon atom hydrocarbon fractions, substantially free from isobutene, which comprises contacting said hydrocarbon fractions under substantially atmospheric pressure with catalytic material comprising essentially a synthetically prepared composite mass of silica, alumina, and thoria at a temperature in the approximate range of 700-1100° F.

5. A process for isomerizing into isobutene a substantial portion of the normal butene content of essentially 4-carbon atom hydrocarbon fractions, substantially free from isobutene, which comprises contacting said hydrocarbon fractions with catalytic material comprising essentially a synthetically prepared composite mass of silica, alumina, and thoria at a temperature in the approximate order of 700-1100° F. under substantially atmospheric pressure for a contact time in the approximate range of 0.01-4.0 seconds.

6. A process for isomerizing into isobutene a substantial portion of the normal butene content of essentially 4-carbon atom hydrocarbon fractions, substantially free from isobutene, which comprises contacting said hydrocarbon fractions with catalytic material comprising essentially a synthetically prepared composite mass of silica, alumina, and thoria at a temperature in the approximate range of 700-1100° F., under a pressure in the approximate order of 0.05-5.0 atmospheres.

7. A process for converting normal butenes into isobutene which comprises contacting said normal butenes under isomerizing conditions with catalytic materials comprising essentially a hydrated silica-alumina-thoria from which alkali metal ions have been removed.

8. A process for converting normal butenes into isobutene which comprises subjecting the normal butene to isomerizing conditions in the presence of a calcined mixture of the hydrogels of silica, alumina and thoria.
